UNITED STATES PATENT OFFICE.

ALICE O. DARLING, OF LEBANON, NEW HAMPSHIRE.

MEANS FOR OVERCOMING INSOMNIA.

1,296,930.

Specification of Letters Patent. Patented Mar. 11, 1919.

Application filed December 12, 1916. Serial No. 136,533. Renewed January 24, 1919. Serial No. 272,968.

To all whom it may concern:

Be it known that I, ALICE O. DARLING, a citizen of the United States, residing at Lebanon, in the county of Grafton, in the State of New Hampshire, have invented a certain new and useful Means for Overcoming Insomnia, of which the following is a specification, reference being had to the accompanying drawings.

10 The immediate object of this invention is to provide simple, inexpensive, and effective means for overcoming insomnia and inducing sleep, and my present improvement briefly described consists of a novel arrangement of bedding whereby an abnormal position of the body is compelled for a time, which tends to divert the attention and thoughts of the would-be sleeper from distracting subjects, and to concentrate his or 20 her thoughts upon the novel position of the body thus temporarily assumed. It is commonly understood by scientists that certain forms of insomnia result from an over-active brain which causes the thinking processes 25 to roam from subject to subject, thus inducing wakefulness, and it is equally well known that concentration of one's thoughts upon a single subject, as for example counting mentally, tends to break up the wandering 30 thoughts, thus finally quieting the brain until the subject finally drops asleep.

The position which the subject assumes while practising this invention also results in relieving all pressure from that portion 35 of the brain known as the medulla oblongata, in which case the subject must fall asleep in a short time.

40 The object of this invention is, mainly, to provide a condition, or position, of the subject, which is unusual to such a degree that the subject's mind dwells upon it, to the exclusion of all diverting thoughts, until sleep comes to the subject.

45 The novel arrangement of bedding, and position of the would-be sleeper, are illustrated in and by the annexed drawings in which Figure 1 is a side elevation of a bed and sleeper arranged in accord with my present improvement, and Fig. 2 is a plan view 50 of the same; the sleeper being shown in dotted outline in both of said figures.

55 Referring to the drawing, the mattress is formed of a plurality of three sections designated as *a*, *b*, *b'*, respectively, the section *a* constituting what may be termed the major portion, or in other words that adapted to

receive the body portion of the occupant thereof. The other two portions or sections of the mattress *b*, *b'*, are arranged at the head-end thereof and are hinged together, as 60 at *d*, whereby the section *b'* may be positioned or swung upwardly and caused to stand edgewise upon the section *b* as seen in Fig. 1, leaving a space *c* intermediate the sections *a* and *b*, the purpose of which will be 65 presently apparent.

The hinge *d* may be a tape, a portion of fabric or any other flexible means for hinging the head sections *b* and *b'* together, and admitting the dropping and sliding of the 70 section *b'* into the opening or space *C*.

As here illustrated, the portion *b* is turned up, on edge, so that its upper edge is located somewhat above the main mattress portion, and so that a considerable space *c* is provided, for the time being, between the two sections *a* and *b*; this being the position to which the small section is adjusted when the would be sleeper finds himself or herself unable to fall asleep. Having thus adjusted 80 the mattress the sleeper turns his body so he is facing downward with his face immediately over the space *c* and with his forehead resting on the raised edge of the mattress section *b* (see Fig. 1); the open space 85 between the sections *a* and *b* permitting him to breathe freely, and the elevated support for his head causing him a slight discomfort which keeps the subject's mind fixed upon that one idea or fact, to the exclusion 90 of all distracting thoughts, until the brain becomes quieted and sleep comes to the subject.

95 The shorter mattress section *b* is, preferably, formed of two hinged portions which are so arranged that the upper portion (upon which the subject's forehead rests) may be folded down into the space *c*, thus conforming the several mattress sections into one level structure. I find in practice that the 100 subject is usually conscious of the fact that he is about to fall asleep, and will then raise his head sufficiently to permit the upper half of section *b* to fall to its closed position, as indicated by dotted lines in Fig. 1, when the 105 head of the subject may settle down upon the mattress thus leveled, or upon a pillow which may be placed thereon.

Having thus described my invention, I claim as new and wish to secure by Letters 110 Patent:—

1. A mattress comprising a major body

supporting portion, and a two-part hingedly connected head portion, the outer part of the head portion being stationary and spaced from the adjacent end of the major portion 5 and the other part of the head portion being adapted to be raised upon the first part into position for receiving the forehead of a person lying face down on the mattress to elevate the head and to provide an air space 10 beneath the head and between the head and major portions of the mattress.

2. A mattress comprising three sections, one section being elongated and adapted to support the body, the second section being

short and lying substantially in the plane 15 of the body supporting section and being spaced from the upper end thereof, and the third section being short and adjustably connected to the second section and adapted to be fitted in the space between the first and second sections, the third section also being adapted to be adjusted upon the top of the second section in position to receive the forehead of a person lying face down on the mattress and support the head in a raised 20 25 position over the space between the first and second sections.

ALICE O. DARLING.
